(57) **CLAIM**

The ornamental design for a speaker or waveguide, as shown and described.

DESCRIPTION

FIG. 1 is a front perspective view of a speaker or waveguide, according to an embodiment;

FIG. 2 is a front elevation view of FIG. 1;

FIG. 3 is a top view of FIG. 1;

FIG. 4 is a bottom view of FIG. 1;

FIG. 5 is a left side view of FIG. 1;

FIG. 6 is a right side view of FIG. 1;

FIG. 7 is a rear view of FIG. 1;

FIG. 8 is a section view taken along section line 8-8 in FIG. 2; and,

FIG. 9 is a section view taken along section line 9-9 in FIG. 2.

The broken lines depict portions of the speaker or waveguide that form no part of the claimed design.

1 Claim, 9 Drawing Sheets
